UNITED STATES PATENT OFFICE

167,945

HEIGHT RECORD CHART

Tage Larson, Milwaukee, Wis.

Application May 14, 1952, Serial No. 19,711

Term of patent 3½ years

(Cl. D52—1)

To all whom it may concern:

Be it known that I, Tage Larson, a subject of the king of Sweden, residing at Milwaukee, Milwaukee County, State of Wisconsin, have invented a new, original, and ornamental Design for Height Record Chart, of which the following is a specification, reference being had to the accompanying drawings, forming a part hereof.

Fig. 1 represents a view of the bottom end and lower intermediate section of a height record chart, showing my new design.

Fig. 2 represents a view of the upper intermediate section and upper end of the chart.

Fig. 3 is an end view.

The reverse side of the chart is plain.

I claim:

The ornamental design for a height record chart, substantially as shown and described.

TAGE LARSON.
